UNITED STATES PATENT OFFICE.

GEORGE P. THOMAS, OF GLENSHAW, PENNSYLVANIA.

METAL-PUNCHING MACHINE.

Application filed March 28, 1923. Serial No. 628,203.

To all whom it may concern:

Be it known that I, GEORGE P. THOMAS, a citizen of the United States, and a resident of Glenshaw, in the county of Allegheny and State of Pennsylvania, have invented a new and useful Improvement in Metal-Punching Machines, of which the following is a specification.

The invention relates to machinery for punching rivet and bolt holes in metal blanks, particularly in structural material such as steel plates, angles, beams and other sections.

In machinery of this sort it is now common practice to provide a work-supporting table at each side of a punching machine, and to provide means for mechanically moving a blank predetermined distances upon the table so that the blank may be in proper position to be punched at the required intervals. For most classes of work, the punches and their cooperating dies are immovably attached to the punching machine so that the holes which are punched in a blank lie in straight lines when the blank is moved in a straight line through the machine. However, in some classes of work it is desirable to punch a line of holes lying in a curve or in an irregular line, and for this purpose the punches and dies are, in some cases, mounted for transverse movement upon the head and anvil of the machine, and means are provided for moving them laterally the required amounts while the machine is in operation. These transverse movements have been effected manually, as by means of threaded rods which engage threaded openings in the tool holders, and have also been effected mechanically. However, the latter has been done by the use of complicated mechanism which has proven to be quite unsatisfactory, both from the viewpoint of the initial cost of construction, and from that of performance in operation.

The object of this invention is to provide a machine for punching an irregular line or lines of holes in a metal blank, which machine is simple in construction, and direct, positive and accurate in operation, and which may also be used for punching holes all lying in straight lines.

A further object is to provide a machine for punching an irregular line or lines of holes in a blank, in which machine cooperating punching tools are moved trans-

versely by a guide movable longitudinally of and with the blank, which guide may be especially constructed for the purpose or may consist of an irregular structural part formed for attachment to the blank being punched.

The invention is illustrated in the accompanying drawings of which Fig. 1 is a somewhat diagrammatic side elevation of a punching machine and work-supporting tables adjacent to it; Fig. 2 a plan view of the construction illustrated in Fig. 1; Figs. 3 and 4 transverse sectional views taken, respectively, on the lines III—III and IV—IV, Fig. 2, Fig. 5 a horizontal sectional view taken on the broken line V—V, Fig. 4; and Fig. 6 a vertical sectional view taken on the broken line VI—VI, Fig. 5.

In the practice of the invention one or more pairs of cooperating punching tools are moved transversely by means of a guide which is moved longitudinally by the blank-moving means and in alignment with the advancing blank, there being suitable connections extending from the guide to the punching tools to cause the latter to move transversely of the blank as the guide is advanced with the blank. While the guide may, within the scope of the invention, be variously formed, and may be connected in different ways, directly or indirectly, to the blank-moving means, it is preferably of a length co-extensive with that of the blank to be punched and is directly connected to the blank-moving means.

The invention is illustrated in its adaptability to punching an irregular line of holes in the lower edge of a web plate 1 for a railway car sill, shown particularly in Fig. 1, although it is manifestly applicable to punching irregular or curved lines of holes in other structural materials, and in materials for other purposes. The holes required to be punched in sill plate 1 include a straight line of holes 50 adjacent one edge of the plate, and an irregular line 51 adjacent to the other edge, it being understood that such plates are narrower at their ends than at their central portion, as is indicated in Fig. 1.

Plate 1 is shown as resting upon rollers 52 of a work-supporting table extending at each side of a punching machine 2. For convenience, the table at the left hand side of the punch may be designated as a spacing table 3 and that on the right as a trailer

table 4. On the central portion of the spacing table there is diagrammatically represented a spacing carriage 5 to which the forward end of plate 1 is attached by means 5 of clamping jaws 6. The spacing carriage and the table on which it travels may be of any desired form. Examples of suitable carriage mechanism are found in my Patents Nos. 1,068,465, 1,179,475 and 1,245,- 10 15 530, it being characteristic of these spacing carriages that they are advanced either manually, or by motors which are usually mounted on the carriages, and that they are automatically stopped to bring blanks being 20 25 punched to stops at the required successive positions for punching the necessary holes in the blanks. Instead of pulling the blanks by carriages in the manner disclosed in said patents, their full lengths may be supported upon carriages as disclosed in my Patent No. 1,175,196.

The punching machine illustrated in the drawings is of a familiar multiple-punch type, similar to that shown in my Patent 25 No. 1,141,221, comprising a frame 2, a reciprocating head 7 and a stationary anvil 8, Figs. 4 and 6. The reciprocating head is constructed for receiving two lines of punch 30 35 holders, one on each side of the head. One side of the machine is equipped with punch and die holders 9 and 10 for punching odd holes in the plate, these tool holders being clamped to the head 7 and an anvil 8 by means of bolts 11 and 12 in such a manner that during the operation of the machine 40 45 they are not movable laterally. The other side of the machine is provided with a punch holder 13 and a die holder 14, which are also fixed against lateral or transverse movement during the operation of the machine, and accordingly are used for punching a straight line of holes, such as the line 50 in plate 1. On the latter side of the machine there is also mounted a transversely movable 50 55 punch holder 15 and die holder 16, the former being provided with the pin 17 and the latter with a socket 18 for receiving the lower end of the pin, thereby interconnecting the holders for transverse or lateral movements in such a manner that the cooperating tools which the holders carry, namely a punch 19 and a die 20 constantly remain in proper relative positions. These tools are for punching the irregular lines of holes, such as the line 51 in plate 1.

All the punch and die holders may be and preferably are, of the laterally applicable type disclosed in my Patent No. 1,064,- 60 65 397, the stationary holders being clamped in position by means of bolts as previously explained. For holding upon the head and anvil the transversely adjustable punch and die holders 15 and 16, straps or brackets 21 and 22 may be clamped to the vertical faces 65 of the head and anvil in the same manner as

the stationary punch and die holders are clamped to these members. Between these straps and the faces of the head and anvil the punch and die holders 15 and 16 may slide.

To move these slidable punch and die holders, or as many pairs of them as may be desired, the required intervals and at the required time during the operation of the machine, a guide, preferably in the form of a bent angle 23 may be mounted upon the back of a channel 24, Figs. 3, 4 and 5, the forward end of which is attached by clamping jaws 55 to the spacing carriage 5. At the sides of the spacing and trailer tables the flanges of the channel may be supported upon, and guided by, rollers 25 removably mounted upon suitable shafts 26 extending laterally from the work-supporting tables. To further guide the channel adjacent to the point where guide 23 exerts its directing or moving influence upon the transversely movable punch and die, the punching machine may be provided with vertically disposed rollers 27. The movable punch and die holders 15 and 16 may be connected to the guide angle by a block 28 slidably mounted in a bracket 29 and connected to die holder 16 by means of a link 30. The lower face of block 28 is provided with a pair of rollers 31 which engage opposite sides of the vertical leg of the guide angle. Bracket 29 is preferably bolted or otherwise detachably connected to the punching machine frame so that the bracket may be readily removed when it is desired to use the machine for punching blanks with holes all lying in straight lines.

In the operation of the punching machinery in its applicability to the punching of an irregular line of holes 51 in a web plate 1 for a car sill, guide angle 23 may be and preferably is, one of the angles which is subsequently riveted to one of the web plates that is punched. This angle is first punched and is then bent to its required final shape. Thereafter it is bolted to the back of channel 24 in alignment with the plate to be punched. Both plate 1 and channel 24 are connected to spacing carriage 5, and accordingly both are simultaneously and uniformly moved by it. This longitudinal movement of the bent guide angle imparts the proper lateral movement to die holder 16 through the connections previously explained; and the die holder, through the pin and socket connection 17, 18, causes the punch holder to correspondingly move laterally. In this simple but effective manner the punch 19 and die 20 are positively and directly positioned at the required places to punch the irregular line of holes 51 required in the plate. Simultaneously with the punching of the irregular line of holes the straight line of holes 50 is punched by the

tools in the stationary punch and the holders 13 and 14. Any odd holes that may be required between lines 50 and 51 may be punched by the tools in the holders 9 and 10 5 on the other side of the machine.

It is characteristic of the invention that the mechanism for moving a punch and die laterally may be applied to existing punching machinery without affecting its capability of being used at any time for 10 punching in the usual manner without lateral movements of any of the tools. It has been previously explained that the punching machine may be of the familiar multiple-punch type. Assuming that the machine has been equipped with the parts necessary to cause one or more pairs of tools to move transversely in the manner explained, all that is necessary to be done in 15 equipping the machine for punching material having holes arranged all in straight lines is to substitute stationary for the laterally movable tool holders, remove bracket 29 and one or both rollers 27 from 20 the punching machine, and, if wide plates or a plurality of narrow blanks are to be punched, substitute work-supporting rolls 52 for the channel or guide supporting rolls 25 on shaft 26.

30 The invention is obviously applicable to punching irregular lines of holes in other than plates for car sills. For example, by providing a curved guide curved lines of holes may be readily punched in the edges 35 of boiler and stack plates. Other uses of the invention will readily suggest themselves to those familiar with the art.

According to the provisions of the patent statutes, I have described the principle and 40 operation of my invention together with what I now consider to represent the best embodiment thereof. However, I desire to have it understood that, within the scope of the appended claims, the invention may be 45 practiced by other forms of construction than that particularly shown and described.

I claim:

1. In machinery for punching an irregular line of holes in a metal blank, the combination of a punching machine equipped with a laterally movable cooperating punch and die, a table extending from opposite sides of the punching machine for supporting a blank, means for moving the blank through 50 the punching machine, a guide longitudinally movable by said blank-moving means in alignment with the advancing blank, and means for connecting said guide to said punch and die for moving them laterally as the punching operation proceeds.

2. In machinery for punching an irregular line of holes in a metal blank, the combination of a punching machine equipped with a laterally movable cooperating punch 55 and die, a table extending from opposite

sides of the punching machine for supporting a blank, means for moving the blank through the punching machine, a guide longitudinally movable by said blank-moving means in alignment with the advancing blank, 70 a member slidably engaging said guide and mounted on the punching machine for movements transverse to that of the guide, said member being connected to said punch and die, whereby the longitudinal movement of the guide imparts lateral movements to the punch and die.

3. In machinery for punching an irregular line of holes in a metal blank, the combination of a punching machine equipped with a laterally movable cooperating punch and die, a table extending from opposite sides of the punching machine for supporting a blank, means for moving the blank through the punching machine, a guide longitudinally movable by said blank-moving means in alignment with the advancing blank, 75 a bracket removably attached to said punching machine, a block slidably mounted in said bracket and engaging said guide, and means for connecting said block to said punch and die whereby the longitudinal movements of the guide impart lateral movements to the punch and die.

4. In machinery for punching an irregular line of holes in a metal blank, the combination of a punching machine equipped with a laterally movable punch and die, a table extending from opposite sides of the punching machine for supporting a blank, means for moving the blank through the punching machine, a guide coextensive with the blank to be punched and longitudinally movable by said blank-moving means in alignment with the advancing blank, and means for connecting said guide to said punch and die for moving them laterally as the punching operation proceeds.

5. In machinery for punching an irregular line of holes in a metal blank, the combination of a punching machine having a reciprocating head and an anvil provided with a laterally movable punch and die, a work-supporting table extending from opposite sides of said machine, a spacing carriage borne by said table on one side of the machine, a guide coextensive with a blank to be punched connected to and longitudinally movable by and with said carriage, and means for connecting said guide to said punch and die for moving them laterally as the punching operation proceeds.

6. In machinery for punching an irregular line of holes in a metal blank, the combination of a multiple punching machine having a reciprocating head and an anvil provided with a laterally movable punch and die, a work-supporting table extending from opposite sides of said machine, a spacing carriage borne by said table on one

side of the machine, said table being provided at each side of a machine with means for supporting a guide, a guide resting upon said guide support and connected at one end to said carriage, said guide being coextensive with a blank to be punched and longitudinally movable with said carriage, and means for connecting said guide to said punch and die for moving them laterally during the punching operation.

7. In machinery for punching an irregular line of holes in a metal blank, the combination of a multiple punching machine equipped with a laterally movable punch and die, a table extending from opposite sides of said machine and provided with work-supporting rolls at one side and with guide-supporting rolls at its other side, means arranged centrally of said table for moving a blank through the punch, a guide mounted upon said guide-supporting rolls and longitudinally movable by said blank-moving means in alignment with the advancing blank, and means for connecting said guide to said punch and die for mov-

ing them laterally during the punching operation.

8. In machinery for punching an irregular line of holes in a metal blank, the combination of a punching machine having a reciprocating head and anvil provided with a laterally movable punch and die, a work-supporting table extending from opposite sides of said machine, a spacing carriage on said table at one side of the punch, a guide coextensive with a blank to be punched connected to and longitudinally movable with said carriage, a bracket removably attached to said punching machine, a block slidably mounted in said bracket and engaging said guide, and means for connecting said block to said punch and die whereby by the longitudinal movements of the guide impart lateral movements to the punch and die.

45 In testimony whereof, I sign my name.

GEORGE P. THOMAS.

Witness:

EDWIN O. JOHNS.
